UNITED STATES PATENT OFFICE

ISAAC H. CREECH, OF CUMBERLAND, KENTUCKY

LIQUID-DISPENSING APPARATUS

Application filed April 27, 1928. Serial No. 273,258.

The present invention relates to liquid dispensing devices for closed containers and has for its principal object to provide a support for the container having a plug adapted to fit within the neck of the container whereby to seal the same and to provide an air vent extending through the plug and upwardly into the container for the purpose of admitting air into the same as the liquid is dispensed therefrom.

A further object of the invention is to provide a filter for the air vent whereby to prevent the entrance of insects or dirt into the container through the air vent while the liquid is being dispensed therefrom.

A still further object of the invention is to provide a discharge faucet attached to the plug and communicating with the interior of the receptacle whereby to enable the dispensing of the liquid therefrom.

A still further object is to provide a device of this character of a simple and practical construction, which provides for the sanitary dispensing of a liquid from the container, which is neat and attractive in appearance, relatively inexpensive to manufacture and otherwise well adapted for the purpose for which the same is intended.

Other objects and advantages reside in the special construction, combination and arrangement of the various elements forming the invention as more fully hereinafter described and claimed, reference being had to the accompanying drawings forming part hereof, wherein like numerals refer to like parts throughout, and in which:

In the drawings:

Figure 1 is a side elevational view showing the device fitted in the neck of one form of receptacle and prior to inverting the same into dispensing position.

Figure 2 is a similar view showing the device supporting the receptacle in dispensing position.

Figure 3 is a perspective view of the receptacle support and plug therefor with the receptacle removed therefrom.

Figure 4 is a bottom plan view, and

Figure 5 is a vertical sectional view through the plug, and with the upper and

lower ends of the air vent broken away and shown in section, whereby to illustrate the manner of controlling the opening in the air vent tube disposed in the interior of the container and also illustrating the construction of the filter arranged at the opposite end of the tube.

Referring to the drawings in detail, the invention comprises a stand composed of a plurality of legs 5 and adapted to support a receptacle in elevated position above the ground, the upper portion of the leg being provided with a cylindrical plug 6 adapted to fit within the neck of a receptacle of a type as shown at 7 whereby to constitute a closure therefor.

The plug 6 is formed with a centrally arranged vertically extending opening 8 within which a pipe section 9 is fitted, the outer end of the pipe being provided with an elbow 10 providing means for attaching the discharge faucet 11 to the pipe and extending toward the side of the plug.

Adjacent the edge of the plug is a sleeve 12 extending vertically through the plug with one end extending a considerable distance within the receptacle 7 and with its inner end closed and terminating in abutting relation with the bottom of the receptacle.

Arranged within the wall of the sleeve 12, adjacent the inner end thereof is an opening 13 adapted to register with a similar opening 14 formed at the inner end of a hollow pipe 15 telescopically arranged within the sleeve and having its outer end extending at right angles therefrom and fitted with a hollow cap 16 having its outer end perforated as shown at 17.

The interior of the cap 16 is adapted to carry a quantity of filtering material 18 loosely packed within the cap and adapted to prevent the package of fallen matter to the pipe 15. The cap 16 also serves as a handle for rotating the pipe 15 within the sleeve 12 so as to move the openings 13 and 14 into or out of registering position with respect to each other whereby to open communication through the pipe 15 to the interior of the receptacle 7.

In the operation of the device the recep-

tacle 7 is arranged with its neck end uppermost and the plug 6 is then fitted therein to form a liquid tight seal for the neck of the receptacle and after turning the pipe 15 so as to move the openings 13 and 14 out of registering position the receptacle is then inverted and supported upon the leg 5.

By reason of the relatively small opening formed by the pipe 9 and by preventing air from entering the receptacle through the pipe 15, the flow of liquid through the faucet 11 will be retarded. However upon turning the pipe 15 so as to bring the openings 13 and 14 into registering position air will be admitted into the upper portion of the receptacle and the liquid will then freely flow from the faucet 11. By admitting the air through the filtering material 18 in the cap 16 the entrance of foreign matter, such as dirt or insects into the contents of the receptacle is thus prevented as the liquid is discharged therefrom.

It is obvious that my invention is susceptible to various changes and modifications in construction without departing from the spirit of the invention or the scope of the appended claim, and I accordingly claim all such forms of the device to which I am entitled.

Having thus described my invention, what I claim as new is:

A device of the class described comprising a plurality of supporting legs having a cylindrical plug formed at the upper portion thereof, said plug being arranged for fitting in the neck of a receptacle to form a liquid tight seal therefor and said plug and said leg cooperating to support the receptacle in inverted position, a discharge pipe extending vertically through said plug and communicating with the interior of the receptacle, a vent pipe extending vertically through the plug with its inner end formed with an opening and disposed adjacent the top of the receptacle when in inverted position, a tube disposed within the pipe and adapted for rotary movement, said pipe and said tube having registerable openings at their ends remote from the plug, whereby to control atmospheric communication with the interior of the receptacle, and a lateral extension formed on the outer end of the tube providing a hand grip for manually operating said tube.

In testimony whereof I affix my signature.
ISAAC H. CREECH.
